UNITED STATES PATENT OFFICE.

GEORGE E. PRENTICE, OF NEW BRITAIN, CONNECTICUT, ASSIGNOR TO THE G. E. PRENTICE MANUFACTURING COMPANY, OF NEW BRITAIN, CONNECTICUT, A CORPORATION.

HOSE-SUPPORTER STUD AND LOOP.

1,170,782.

Specification of Letters Patent. Patented Feb. 8, 1916.

Application filed February 5, 1915. Serial No. 6,346.

To all whom it may concern:

Be it known that I, GEORGE E. PRENTICE, a citizen of the United States, residing at New Britain, in the county of Hartford and 5 State of Connecticut, have invented certain new and useful Improvements in Hose-Supporter Studs and Loops, of which the following is a specification.

My invention relates to improvements in 10 hose supporter studs and loops such as are shown and described in my application Serial No. 766,066, filed May 7, 1913, and not claimed therein, and the object of my improvement is to produce a stud member having 15 certain novel structural features which pertain to the same alone and which also coöperate in a peculiar manner with the metallic loop.

In the accompanying drawing:—Figure 1 20 is a front elevation of a garter clasp having a hose supporter stud member embodying my invention and the webbing and part of the garter. Fig. 2 is a sectional view on an enlarged scale on the line $\alpha\alpha$ of Fig. 1. 25 Fig. 3 is a front elevation of the stud member, and part of the loop partly in section. Fig. 4 is a bottom view of the same. Fig. 5 is a plan view of the same with the cushion member removed, the loop being shown in 30 broken lines. Fig. 6 is a bottom view of the same, the loop being shown in section. Fig. 7 is a sectional view on an enlarged scale on the line yy of Fig. 3, the loop being omitted.

The garter clasp shown in the drawing 35 comprises a stud member A and a metallic loop B operatively connected together and to the garter C by means of a webbing D. The webbing D comprises a downwardly extending loop at the apex of which the stud member A is supported and having a rear arm or reach 16 which is essentially straight and a front arm or reach 17 which adjacent the apex is threaded through the slots 18 in 40 the body plate 19 of the stud member A and which above the stud member A engages the upper end of the metallic loop B by means of an auxilliary or intermediate loop or bight 20 in an ordinary manner. The metallic loop B is suitable for engaging with 45 the button F, which latter is constructed and cushioned in a manner to be described.

The stud member A comprises the body plate 19 already mentioned and having a

hole 23 at the middle in which is secured the 55 core member 21 and which extends outwardly therefrom. On the core member is mounted the cushion member 22. The webbing slots 18 in the body plate 19 are positioned one above and the other below the 60 core member 21. The core member 21 comprises a body portion or barrel 24 which is in the form of a cylindrical shell having a thin side wall inclosing an open space or bore 26 extending therethrough. The inner end 65 portion of the barrel 24 is a fit for the hole 23 and extends therethrough and the extreme inner end 29 is headed over against the rear face of the body plate 19. At the outer end the core member 21 is provided 70 a set of radial projections 30 shown as three in number and which extend outwardly and overhang the lateral walls of the barrel 24, essentially on all sides.

The cushion member 22 comprises a head 75 31 which incloses the outer end of the core member 21, the radial projections 30, which latter are embedded therein; and a portion of the barrel 24, and a shank 32 which extends over the portion of the barrel 24 between the head 22 and the body plate 19.

The metallic loop B comprises as usual a relatively narrow portion or bight at the lower end composed of the apex 36 at the extreme lower end and the two upwardly 80 extending arms 37, suitably spaced to receive between them the barrel 24, the shank 32, and the material of the hose.

I prefer to have the spread or spacing 90 of the arms 37 such that when in position on the barrel 24 each of the said arms will be positively overhung by some part of the radial projections 30. I also prefer to have the cushion member 22 vulcanized to the core member 21 so as to make a unitary 95 structure of these parts. With the cushion member 22 vulcanized to the core member 21 as mentioned the inner end 28 of the shank 32 bears against the front face of the body plate 19 and serves as an annular shoulder and in coöperation with the headed over or riveted extreme inner end 29 of the barrel 24 in holding the button F in position on the body plate 19. Accordingly, as described, when the loop B is in engaging 100 position with the button F the shank portion 32 of the cushion member 31 is interposed between the arms 37 thereof and the

core member 21. That is to say, there is rubber between these parts, as the cushion member is preferably made of rubber. At the same time, the projection 30 extends a sufficient distance laterally to positively overhang both of the said arms 37, and while the said arms are engaged as described with the shank 32 and the barrel 24 on which the same is mounted. This insures a positive holding of the loop on the button, independently of the material of the head 22. Whatever of such material of the head 22 as may be interposed between the arms 32 and the projections 30 is subjected to compression merely, without any tendency to stretch or tear or twist.

In the construction of the stud member A the cushion member 22 is mounted on the core member 21, leaving the inner end portion exposed. Then the said inner end portion is inserted in the hole 23 of the body plate 19 with the inner end of the shank 32 in abutment therewith, and then the extreme inner end 29 is headed over. Thus it will be noted that the shank 32 serves as one of the means for positioning the stud or button on the body plate 19. This permits of a cylindrical form for the entire length of barrel portion 24 of the stud member 21. As stated the barrel portion 24 is a fit for the hole 23 through which it extends. The headed end 29 serves to position the barrel portion or core member relatively to the body plate 19 on one side, and the barrel portion 24 is otherwise generally free to slip through the said hole 23, on the other or outer side of the body plate 19. The positioning of the core member relatively to the said body plate is effected by the shank 22 of the cushion member which, as stated, is secured thereto by vulcanizing. As the cushioning member is made of yielding material, the core member and the cushion member supported thereby, are yieldingly supported relatively to the body plate.

Actually there is a slight give of the unit represented by the cushion member and the core member on which it is mounted and the

body plate 19, so that when pressure is applied to the head 31 of the cushion member the said unit will move bodily inwardly. This effect is rendered possible by the construction described, which of course involves the avoidance of the formation of a positive metallic shoulder on the barrel portion on the side of the body plate on which the cushion member is mounted.

The fact that the head 31 is closed, and continuous, and extends over the outer end of the barrel member and is crowned at the outer face cooperates to effect a yielding condition of the cushion member in the longitudinal direction, relatively to the body plate, as the portion of the head that bridges the opening in the end of the tubular barrel portion will also yield under pressure.

In use the head 31 is particularly exposed, and liable to come into contact, through interposed garments of course, with obstructions, so that the double yielding effect described serves to relieve the shock due to such contact.

I claim as my invention:—

In a stud and loop combination, a stud member comprising a body plate having a hole and a unitary structure mounted thereon comprising a core member and a cushion member supported thereby, the said core member comprising a tubular barrel portion of uniform cross-section having an open outer end and fitting and extending through the said hole and having the inner end headed over suitably to engage with the rear face of the body plate, the said cushion member comprising a head portion closing the outer end portion of the said core member and a shank portion extending from the said head portion along the said barrel portion, and the said shank portion having the inner end engaged with the opposed face of the said body plate.

GEORGE E. PRENTICE.
